[57] CLAIM

[**] Term: 14 Years

The ornamental design for a blood chemistry sensor
assembly, as shown and described.

[21] Appl. No.: 1,462

DESCRIPTION

[22] Filed: Nov. 13, 1992

FIG. 1 is a front elevational view of a blood chemistry
sensor assembly embodying our new design;

[52] U.S. Cl. D24/108

FIG. 2 is a top plan elevational view thereof;

[58] Field of Search D24/108, 111, 107;
128/635, 760, 630, 632, 637; 604/4, 67;
204/409, 411, 412, 401, 403, 195 R

FIG. 3 is a left side elevational view thereof;

[56] References Cited

FIG. 4 is a right side elevational view thereof;

U.S. PATENT DOCUMENTS

FIG. 5 is a rear elevational view thereof;

4,573,968 3/1986 Parker 604/67
4,854,322 8/1989 Ash et al. 128/635

FIG. 6 is a bottom plan view thereof; and,

FIG. 7 is a top, front perspective view thereof.

The broken line showing of the tube in FIGS. 1, 3, 4 and
5 is for illustrative purposes only and forms no part of

the claimed design.

FIG. 2.

FIG. 3.

FIG. 1.

FIG. 4.

FIG. 5.

FIG. 6.

FIG. 7.
